UNITED STATES PATENT OFFICE.

FREDERICK ERNEST CLIFT, OF BROOKLYN, NEW YORK, ASSIGNEE TO ADVANCE MACHINE WORKS, INC., OF BROOKLYN, NEW YORK, A CORPORATION OF NEW YORK.

SEAMING MACHINE.

Application filed April 29, 1926. Serial No. 105,353.

My invention relates to seaming machines, and more particularly to machines such as disclosed in United States patent to Ross, No. 1,469,334 for fixing the ends or heads 5 of cans to the sides or bodies thereof.

Heretofore when the cans of certain shapes, for example, cans long and narrow in horizontal cross section, have been made in machines of the character referred to, it 10 has frequently been found that the seam was not tightly closed at certain points.

One object of the invention is to improve such machines so as to avoid the production of defective seams. Another object of the 15 invention is to provide improved means for adjusting the seaming mechanism without interfering with the accuracy of the operation thereof.

Other objects, features and advantages 20 will appear more fully in the following detailed description and appended claims.

The drawings forming a part of this specification illustrate one embodiment of the invention. In the drawings

25 Figure 1 is a top plan view of a part of the head of a seaming machine; and

Figure 2 is a side elevation of the same, partly in section.

The can or other article operated upon 30 is supported upon a table or base (not shown) which may be constructed and arranged as shown in the aforesaid patent to Ross, No. 1,469,334. The head of the machine contains a member 10 which has a 35 chuck portion 11 to hold the can body and end assembled while being operated upon. The member 10 is carried by a stud 12 forming a fixed or stationary part of the machine. Rotatively mounted upon the member 10 and stud 12 is a disc or head member 40 14. At spaced points around the member 14 are arranged sets of devices for controlling the seaming tools. Except for the tools per se, the devices referred to are identical, 45 and I shall accordingly describe only one of these devices.

Lever 15 arranged on the under side of the rotatable member 14 is supported from that member by the vertical pivot 16 which 50 passes into the member 14 and is secured in place by nut 17 and lock nut 18. The free end of lever 15 carries a roller 19 adapted to run in a cam groove 20 in the bottom of the member 10. This groove is 55 made to conform to the outline of the can,

so that when the disc or movable head member 14 rotates about the stud 12, the roller follows a path coinciding with the outline of the can. As shown, the outline is rectangular, the cam groove being coaxial with the member 14. The lever 15 has pivoted thereto, intermediate its ends, as at 21, another lever 22. The inner end of the lever 22 carries a seaming tool 24 which, as shown, is in the form of a narrow roller rotatable 60 above a vertical axis. The other end of the lever 22 carries a thrust or bearing block 25 which bears against an adjustable bearing block 26 carried by the lower arm 27 of a lever which has a vertical pivot portion 28 extending through the rotatable head member 14 and which has secured to the upper end thereof lever arm 29. The arm 29 carries a rotatable follower 30 which is arranged to coact with a cam 31. The 65 block 26 is made adjustable in order to permit adjustment of the position of the tool with respect to the work. To this end the block is carried by adjusting screw 31' rotatable in lever arm 27. A lock nut 32 serves to hold the screw 31' and the block 26 in position with respect to the lever arm 27. The various tools 24 are designed and arranged to effect the desired shaping of 70 the metal to form the seam between the head and body. For example, when three of these tools are used, the first may be employed to effect a preliminary turning down of the metal at the seam, the second to perform an intermediate shaping and the third to finish 75 the seam, all as more fully described in the aforesaid patent to Ross. During the rotation of the head member 14 the tools 24 together with the levers 22 supporting the same take their general direction of movement from the lever 15 whereby the tools 24 are caused to move in approximate coincidence with the contour of the article to be seamed. The actuation of the tools whereby 80 they are caused to change the shape of the metal is imparted thereto by the action of cam 31 on levers 29, 27 whereby the tool supporting levers 22 are shifted upon their pivots 21 so as to move the tools towards 85 the article being operated upon.

The head member 14 is provided with a gear 34 which is secured to the said member and may be rotated by suitable mechanism (not shown), for example, as shown in the said patent to Ross. In order to ef- 90 95 100 105 110

fect the movement of levers 29 by the cam 31, the said cam is provided with a gear 35 which may be rotated with respect to head member 14 by suitable mechanism (not shown), for example, as shown in the said patent to Ross.

Referring to Fig. 1, it will be seen that as the tool 24 is moved inwardly by movement of the tool carrying lever 22 about its axes 10 21 during the formation of the seam, the tool moves approximately in a straight line extending from the axis of the tool to the vertical axis of the can or other article operated upon, the pivotal axis of the lever 22 15 and the axis of the tool being arranged in a vertical plane substantially at right angles to the plane passing through the axes of the tool and of the article. This results in the formation of a very tight seam. It 20 will also be noted that the pivotal axes of the levers 22 and 15 and the axes of the roller 19 and tool 24 are in the same vertical plane when lever 22 is in its normal position directly under lever 15 and that movement 25 of the lever 22 about its axis causes the tool to move directly towards or away from the vertical axis of the article being operated upon.

The bearing surface 25 on the lever 22 is, 30 as shown, in the shape of a vertical semi-cylinder having its axis located in coincidence with the pivotal axis of the lever 15 when the lever 22 is in its normal position directly under the lever 15. As a result of 35 this arrangement oscillation of the lever 15 about its pivotal axis as the roller follows the contour of the groove 20 necessitates no change in position between lever arm 27 and the tool supporting lever 22. The block 26 40 has a flat bearing surface in engagement with the bearing member 25 so that these surfaces have an extended contact with each other and there is no objectionable wear between them. The part 25 and the adjusting block 26 may be made of suitable wear-resisting material such as tool steel. Adjustment of the block 26 with respect to the arm 27 causes the block to move in a line which 45 extends through the axis of the bearing 25 when the lever 22 is in its normal position under lever 15 so that the positioning of the tool 24 is effectively accomplished by such adjustment. I have found that by employing adjusting means described, objectionable 50 wear is avoided and the parts may be easily maintained in proper relation to each other.

In operation, rotation of the head 14 and of the cam 31 causes the tools 24 to move along the seam between the body and end 60 of the can and to close down the seam in the manner described in the aforesaid patent to Ross. I have found that even where the article operated upon is of unusual shape, such as a wide can of slight thickness, a 65 tight seam is effectively produced, and that

accurate adjustment of the parts may be readily made.

It is to be understood that modifications coming within the scope of the appended claims may be made without departing from the spirit and scope of the invention.

What I claim as new and desire to secure by Letters Patent of the United States is:

1. The combination of a seaming tool, a support therefor, means for guiding said support to move said tool in approximate coincidence with the contour of the article to be seamed, and means for shifting said support to cause said tool to move substantially in a line extending from the tool to the axis of the article to perform a seaming operation.

2. The combination of a seaming tool, a lever supporting the same, means for guiding said lever to move said tool in approximate coincidence with the contour of the article to be seamed, and means for shifting said lever to cause said tool to move substantially in a line extending from the tool to the axis of the article to perform a seaming operation.

3. The combination of a seaming tool, a support therefor, means including a lever carrying said support and a cam coacting with said lever for guiding said support to move said tool in approximate coincidence with the contour of the article to be seamed, and means for shifting said support to cause said tool to move substantially in a line extending from the tool to the axis of the article.

4. The combination of a support for an article to be seamed, a seaming tool, a lever supporting said tool, means for guiding said lever to move said tool in approximate coincidence with the contour of the article, the pivotal axis of said lever and the axis of said tool being arranged in a plane substantially at right angles to the plane passing through the axes of the tool and of the article, and means for shifting said lever about its pivotal axis.

5. The combination of a support for an article to be seamed, a seaming tool, a lever supporting said tool, a second lever supporting said tool supporting lever for pivotal movement about an axis intermediate its ends, means coacting with said second lever for guiding said levers to move said tool in approximate coincidence with the contour of the article, the pivotal axes of said levers and the axis of said tool being substantially in the same plane located substantially at right angles to the plane passing through the axes of the tool and the article, and means for shifting said tool supporting lever about its pivotal axis to move the tool towards the article.

6. The combination of a support for an article to be seamed, a seaming tool, a lever

supporting said tool, a second lever supporting said tool supporting lever for pivotal movement about an axis intermediate its ends, means coacting with said second lever for 5 guiding said levers to move said tool in approximate coincidence with the contour of the article, the pivotal axes of said levers and the axis of said tool being substantially in the same plane located substantially at 10 right angles to the plane passing through the axes of the tool and the article, and means including a cam and a lever actuated thereby for shifting said tool supporting lever about its pivotal axis to move the tool towards the 15 article.

7. The combination of a support for an article to be seamed, a seaming tool, a lever supporting said tool, a second lever supporting said tool supporting lever for pivotal 20 movement about an axis intermediate its ends, means coacting with said second lever for guiding said levers to move said tool in approximate coincidence with the contour of the article, the pivotal axes of said levers and 25 the axis of said tool being substantially in the same plane located substantially at right angles to the plane passing through the axes of the tool and the article, means including a cam and a lever actuated thereby for shifting said tool supporting lever about its pivotal axis to move the tool towards the article, and means including an adjustable member carried by said cam actuated lever and coacting with said tool supporting lever for 30 adjusting said tool with respect to the article.

8. The combination of a seaming tool, a support therefor, means including a lever for guiding said support to move the tool in approximate coincidence with the contour of 40 the article to be seamed, said support having a bearing surface curved about an axis normally substantially coincident with the pivotal axis of said guiding lever, and means for shifting said support relatively to said 45 guiding lever, said last named means including an adjusting member coacting with said bearing surface.

9. The combination of a seaming tool, a lever supporting the same, means including 50 a lever for guiding said tool supporting lever to move the tool in approximate coincidence with the contour of the article to be seamed, said tool supporting lever having a bearing surface curved about an axis nor-

mally substantially coincident with the pivotal axis of said guiding lever, and means for shifting said tool supporting lever relatively to said guiding lever, said last named means including an adjusting member coacting with said bearing surface. 55

10. The combination of a seaming tool, a lever supporting the same, means including a lever for guiding said tool supporting lever to move the tool in approximate coincidence with the contour of the article to be seamed, 60 said tool supporting lever having a bearing surface curved about an axis normally substantially coincident with the pivotal axis of said guiding lever, and means for shifting said tool supporting lever relatively to said 65 guiding lever, said last named means including an adjustable bearing block coacting with said bearing surface. 70

11. The combination of a seaming tool, a lever supporting the same, means including a lever for guiding said tool supporting lever to move the tool in approximate coincidence with the contour of the article to be seamed, said tool supporting lever having a cylindrical bearing surface curved about an 75 axis normally substantially coincident with the pivotal axis of said guiding lever, and means for shifting said tool supporting lever relatively to said guiding lever, said last named means including an adjustable bearing 80 block having a flat bearing surface in engagement with said cylindrical bearing surface. 85

12. The combination of a seaming tool, a lever supporting the same, means including a lever for guiding said tool supporting lever to move the tool in approximate coincidence with the contour of the article to be seamed, said tool supporting lever having a cylindrical bearing surface curved about an axis normally substantially coincident with the pivotal axis of said guiding lever, and means for shifting said tool supporting lever relatively to said guiding lever, said last named means including an adjustable bearing block 90 having a flat bearing surface in engagement with said cylindrical bearing surface, said block being adjustable in a line extending substantially through the pivotal axis of said 95 guiding lever. 100

In testimony whereof, I have signed my name to this specification.

FREDERICK ERNEST CLIFT.

CERTIFICATE OF CORRECTION.

Patent No. 1,660,547.

Granted February 28, 1928, to

FREDERICK ERNEST CLIFT.

It is hereby certified that the assignee in the above numbered patent was erroneously described and specified as "Advance Machine Works, Inc.", whereas said assignee should have been described and specified as "Adriance Machine Works, Inc.", as shown by the records of assignments in this office; and that the said Letters Patent should be read with this correction therein that the same may conform to the record of the case in the Patent Office.

Signed and sealed this 17th day of April, A. D. 1928.

(Seal)

M. J. Moore,
Acting Commissioner of Patents.
